WEDGE VISE

Gordon E. Paulson, Fairview, Pa., assignor to
Paul S. Paulson, Rochester, N. Y.

Application January 10, 1947, Serial No. 721,261

1 Claim. (Cl. 81—26)

1

This invention relates to improvements in work clamping devices and more particularly to vises and the like.

A primary object of this invention is the provision of an improved vise construction wherein the direction of application of force tends to close the vise jaws in a direction substantially at right angles to the path of travel of the jaws.

A further object of the invention resides in the provision of an improved structure accomplishing the application of such force.

An additional object is the provision of an improved vise which is sturdy and durable in construction, reliable and efficient in operation and relatively simple and inexpensive to manufacture and assemble.

With the above and other objects in view my invention consists in the combination, arrangement and details of construction disclosed in the drawings and specification and then more particularly pointed out in the appended claim.

In the drawings, wherein similar reference characters designate similar parts throughout the respective views:

Figure 1 is a perspective view of one form of my invention, partly broken away,

Figure 2 is a cross section taken on the line 2—2 of Figure 1, partly broken away,

Figure 3 is a perspective sectional detail view of a slide with associated jaw, taken on the line 3—3 of Figure 1

Figure 4 is a fragmental cross sectional view of a jaw and its mounting, taken on the line 4—4 of Figure 1

Figure 5 is a perspective view of a modified form of my invention,

Figure 6 is a fragmental cross sectional view taken on the line 6—6 of Figure 5, and

Figure 7 is an exaggerated detail cross sectional view of one end of the vise, as taken on the line 7—7 of Figure 5.

In the drawings, which are merely illustrative of my invention, I disclose the various features thereof. A sturdy frame or upright standard is provided of U-shaped cross-section having the base portion 10 and oppositely arranged side walls 11 and 12 with an intervening space 13 between them. The walls 11 and 12 are formed centrally with the slotted portions 14 and 15 for insertion or introduction of the work therein; whereby end props 16 and 17 are provided upon the frame, while upon the upper edges and opposite ends of side walls 11, 12 are formed rectangular recesses 18 and 19, respectively, vertical edges of which form stop shoulders 20.

2

Rectangular blocks 21 and 22 extend across the space 13 of the frame so that their ends rest upon the bottom edges of the rectangular recesses 18 and 19 respectively, while their outer long edges 25 abut the stop shoulders 20. Upon their long inner edges these blocks are formed with elongated grooves 23. Fasteners 24 rigidly secure these blocks upon the frame.

I provide a fork shank 26 for a fork having 10 the oppositely arranged and separated arms 28 and 29 and the cross web 27 connecting them. Outer edges 33 of said fork arms are parallel and are formed with integral tenons 30 which are slidably dovetailed into the grooves 23 of the blocks 21, 22 respectively. The inner edges of these fork arms are wedge-shaped and so incline in opposite directions as at 31 and 32. The ends of the work arms also slidably project into the frame rectangular recesses 19 and 18 which 15 act as guides therefor to allow the fork to slide in a plane at right angles to the length of the frame.

There is a pair of oppositely arranged slides 34 and 35 having outer long edges 36 which incline 20 in the same direction as the inclined edges 31, 32 of the arms of the fork which they abut and having their flat opposite ends slidably guided between adjacent parts of walls 17, 16 of the frame. These flat end walls of the slides are formed with grooves 37, 38 respectively, while the slides rest upon shoulders 39 of the frame walls, the latter being formed with linear slots 40 in which slide pins 41 are carried by the slides 34 and 35 as a means for guiding the slides.

Associated with the slides are jaws 40 and 41 having flat inner edges which abut the similar edges of the slides, but the outer edges of these jaws incline in opposite directions as at 42, 43 to form gripping surfaces. The opposite ends of these jaws also have grooves 37, 38.

The inner edges of the jaws have projecting tongues or tenons 42' which are received in grooves 45 formed in the slides 34, 35, and a locking pin 44 projects removably into both tongue and slide and has its head abutting the slide. Dies 45a extend into grooves 37, 38 of the jaws for movably guiding them, being secured fixedly in place against the frame walls by means of screws 47 tapped into them and into the walls. Normally, as shown in Figure 1, the work clamping jaws project partially into the work receiving slots 14, 15 in space 13 of the supporting frame.

In Figure 5, I show a modification of my vise invention. A cross bar 50 is secured to oppositely arranged arms 54, 55 of the fork, each of these

arms being triangular-shaped tapering to narrow outer ends 59, their hypotenusal inner edges being wedge-shaped and inclining in opposite directions as at 56. The outer edges of these fork arms are parallel, being slidably guided against adjacent flat sides of the blocks 84 and 85 arranged at the opposite ends of the frame and held in fixed position upon the top edges of the frame by pins 87, the ends of these blocks resting on recessed-out top frame edges 87a. The outer straight edges of the fork arms have tenons 58 which are movably mounted in corresponding grooves formed in the blocks 84, 85, the ends 59 of the fork also resting upon recessed-out top frame edges 87a.

A pair of stout guide blocks 93 are rigidly secured upon seats 39' of sides 11', 12' of the frame by aid of fastening screws 94, and the guide block have grooves 94a into which project slidably a pair of oppositely arranged tenons 80 formed upon movable jaws 75, 76 the inner end edges of which are wedge-shaped so as to incline in opposite directions so as to abut the correspondingly inclined edges 56 of the arms of the fork.

The outer edges of these jaws incline in opposing directions, as at 77, 78, with respect to central vertical grooves 79 formed in these jaws. Normally these jaws project partially in the work receiving slots of the frame. It will be seen from Figure 6 that pins 88 project down into blocks 84, 85 with their heads 86b abutting the top thereof. Pins 83 similarly project down into and from jaws 75 and 76 with their heads 82 resting upon the tops thereof. A pair of strong coiled springs 91 have one end each secured to one pin 88 and have their other ends secured to one pin 83 in the jaw adjacent to pins 88. Normally these springs hold the jaws pressed against the inclined edges of the arms of the fork.

The cross bar 50 of the fork is formed centrally with a cross cut recess 51, 52, which opens out at 53 of the cross bar. Rotatably received into this cross cut recess is the disk 60 of the fork actuating screw 61 which is threaded into the fixed die 62 whose oppositely arranged base flanges 63 are secured by screws 64 in top edge recesses 68 formed upon a frame 65 which is rigidly connected to frame 10 at right angles thereto laterally. The threads of the screw are designated 61. At the outer end of screw 61 is a cylindrical terminal 70 which projects into a socket in a center piece 74 in which is a through hole 75 into which projects adjustably the operating crank handle rod 72 having the ball ends 74 engaged on studs 73 at the end thereof. It is understood that any other means may be employed, other than mechanical for actuating the fork, whether hydraulic, pneumatic, magnetic, etc.

The device operates as follows: It will be seen that the jaws are interchangeable. They can easily be replaced if worn. The work is placed in the space 13 of the frame, being insertible through side recesses 14, 15 thereof.

The fork is held against vertical displacement from the frame by its dovetailed connection in the blocks when the proper instrumentality is operated for actuating the reciprocatory movement of the fork, such as by taking hold of crank handle 72 and turning it to advance the screw 61, a thrust is imparted to the wedging fork. It

begins to slide towards the frame supporting it, and as it slides the opposite arms thereof move forwardly between blocks and jaws or jaw-carrying slides as the case may be. As this takes place the oppositely inclined wedging edges of the arms of the fork engage slidably the correspondingly shaped inclined edges of the slides or jaws and thereby urge them forcibly to move towards each other to powerfully clamp or grip the work from opposite points thereof. These jaws move against the tension of the springs 91. As the fork is reciprocated so are the jaws, the spring causing the jaws automatically to retract. Hence the jaws are opened and closed relatively to the work by reciprocating the fork in the manner set forth. The jaws are effectively actuated concentrically of the fork—they advance and retract accordingly as the fork advances or is retracted.

From the foregoing it will be seen that I have provided a vise characterized by the fact that the point of application of the force utilized to operate the jaws is in a plane at right angles to the direction of travel of the work clamping jaws. It will also be seen that the operative or clamping thrust of the vise is such that equal and opposite pressure is imposed upon the two movable jaws at the same time so that a minimum of friction is engendered on the part of the jaw engaging force applying instrumentality.

I do not intend to confine myself to the exact details of construction disclosed, but will cover and include all variations falling within the purview of the appended claim.

What I desire to claim and patent is:

In a device as described, an upright U-shaped frame having a central slot, a pair of props disposed at the opposing ends of the frame and bridging the same, a fork having opposing arms having outer parallel edges slidably dovetailed into said props, and having oppositely inclined inner edges, a pair of separable jaws slidably guided in said frame and having oppositely inclined edges coincidentally engaging the inclined edges of the arms of said fork, pins projecting below said props, pins projecting below said jaws, a spring connecting the pins at each end of the frame and yieldingly pressing the jaws against the arms of said fork, whereby as said fork is thrust forwardly of said jaws the latter are caused to approach each other, against the tension of said springs, and as said fork is retracted relatively to said jaws the latter are forced by said springs to retract in unison therewith, and means for operating said fork.

GORDON E. PAULSON.
